UNITED STATES PATENT OFFICE.

BURNIE L. BENBOW, OF CLEVELAND, OHIO.

PACKING AND PROCESS OF MAKING SAME.

No Drawing.

Application filed March 26, 1921. Serial No. 456,185.

The invention relates to improved packing material suitable for gaskets, rod packings and various other uses, and to a process of making said material.

5 The chief object of the invention is to provide a packing material of the character indicated that has effective liquid and gas sealing qualities and also excellent lubricating qualities and that is durable and capable 10 of being easily produced at low cost.

A further object of the invention is to provide a packing material having satisfactory lubricating properties and which is at the same time highly inert chemically.

15 Another object of the invention is to provide a simple and easily practiced process of producing a packing of the character in question.

My invention involves essentially, first, 20 treatment of a base material that is preferably more or less porous with extremely finely divided graphitic carbon in liquid suspension so as to impregnate the base material with the liquid and carbon of the bath, and 25 second, removing the impregnated base material from the bath and evaporating the liquid from the material so as to leave the base material with a deposit of substantially pure, dry graphite the particles of which strongly 30 cohere to each other to form a strongly coherent coating which strongly adheres to the base material. I have found that deflocculated graphite meets these requirements. By deflocculated graphite, I mean graphite 35 of the character described in United States Letters Patent No. 844,989. Such graphite is very finely divided. For the purpose of my invention the degree of subdivision of the graphite preferably is such that the particles are capable, in the absence of any flocculatory agent, of penetrating the base material wherever the liquid vehicle used is capable 40 of penetrating it.

The base material can be fibrous, as flax, 45 asbestos or metal "wool"; or it can be cellular, as balsa wood; or it can be in powder form, as powdered metal, or it can be any other suitable material having pores or interstices or/and tissues capable of being penetrated by the finely divided graphite.

In preparing my improved packing, I prefer to first form the base material more or less completely to the shape of the finished packing as by weaving, braiding or felting in 55 the case of fibrous material, or turning, boring or otherwise shaping to form in the case

of blocks of cellular material like wood, or pressing, with or without the admixture of a suitable binder, in the case of powdered material. The suitably prepared base material is then immersed in a liquid bath containing the deflocculated graphite in suspension. In preparing this bath, any suitable liquid can be used as the vehicle for the suspension of the graphite, but water is satisfactory and I prefer to use it. The amount of graphite used per unit volume of water can vary from a relatively small amount up to the full amount the water is capable of holding in suspension, and will be determined by the nature of the base material, the thickness of graphite deposit desired, and the use to be made of the packing.

When the base material has become very thoroughly soaked with the liquid, it is removed and the water allowed to evaporate. The dried packing is then found to be impregnated with dry graphite deposited from the liquid vehicle. In the case of a vegetable base material, the deflocculated graphite in suspension not only penetrates the interstices or pores of the material but even the vegetable tissue itself. Thus, in the case of a fibrous vegetable base, the graphite, on evaporating the liquid vehicle, is found not only to be deposited on the fibres so extensively and evenly that each individual fibre of the mass is practically covered with a coating of graphite of which the particles strongly cohere together to form a coating 50 which strongly adheres to the fibres, but even to have penetrated and been deposited in the very tissue of the fibres. Similarly, in the case of a cellular body such as a block of balsa wood, the graphite not only penetrates 55 the open pores of the wood but also the tissue forming the cell walls of the wood, so that the very tissues of the wood as well as its pores are impregnated with the graphite. The adhesion of the graphite to the base material is of course independent of the liquid suspending vehicle or medium as the latter is evaporated out in the process.

In carrying out the immersion treatment of the base material, the impregnation thereof can be hastened and increased by expelling the air from the pores or interstices of the material so that the liquid is free to enter. In the case of a loose porous or fibrous material, such as flax, a vigorous movement 110 or agitation of the material in the bath is sufficient to dislodge and expel the air. In

- the case of denser materials, such as wood blocks or pressed powdered metal or even closely woven or felted fibrous material, better results may be secured by subjecting the
- 5 bath with the packing material therein to the action of a vacuum, thus effectively removing the air from the interstices of the packing material. This vacuum treatment can be used alone or in addition to the agitation
- 10 of the material in the bath. If desired, the vacuum treatment can be followed with the application of pressure to the bath to insure a deep penetration of the liquid in the packing material.
- 15 When the material, treated in the manner described, has dried, it is ready for use. I have found in the use of my improved packing that, with a suitable base material, it has excellent lubricating qualities and, at the same time, is more nearly chemically inert than any other lubricating packing known to me. For example, I have used it very successfully to pack rods or plungers of an oxygen compressor. Again, I find that the packing
- 25 has very effective gas and liquid sealing qualities, this being due, doubtless, to the thorough penetration and impregnation of the interstices and even the tissue of the base material by the graphite. Another important quality of my improved packing is extremely great durability. This I attribute to the fact that the deflocculated graphite when deposited from suspension strongly coheres together to form a coating which strongly
- 30 adheres to the base material. Fibrous packing prepared in accordance with my invention has proven to be very much more durable than any other fibrous packing known to me.
- 35 The process of producing my improved packing, particularly the more commonly used fibrous packing, is obviously extremely simple and inexpensive to work, involving as it does simply the mixing of the deflocculated graphite with water, immersing the fibrous packing material in the liquid bath until it is thoroughly saturated, preferably agitating it in the bath as above described to remove air, removing it from the bath and
- 40 allowing it to dry.
- 45 It will also be obvious that the base material, particularly fibrous material, can be treated either in an unformed mass, or preferably more or less completely formed to the
- 50 shape of the finished packing, as above suggested. One convenient way of making the fibrous packing is to twist or weave the fibrous material into cord form and then immerse the cord in the treating bath. The
- 55 impregnated cord can then be cut to any desired length for the individual packing.
- 60 In the foregoing description of the base material of the packing, I have used the term "porous" in a broad sense to indicate
- 65 any structure characterized by minute open-

ings and corresponding interior spaces and surfaces to which the deflocculated graphite in suspension can penetrate and be deposited.

Various modifications and applications of the invention within the scope of the appended claims will occur to those skilled in such matters.

What I claim is:

1. The process of making packing which includes immersing a base material in a liquid bath containing deflocculated graphite in suspension, removing the base material from the bath, and evaporating the liquid therefrom, thereby leaving thereon a dry adherent coating of graphite.

2. The process of making packing which includes immersing porous material in a liquid bath containing deflocculated graphite in suspension, removing the porous material from the bath, and evaporating the liquid from said material, thereby leaving thereon a dry adherent coating of graphite.

3. The process of making packing which includes immersing porous material in a liquid bath containing deflocculated graphite in suspension, removing air from the interstitial spaces of the material to permit the liquid of the bath to enter said spaces, removing the porous material from the bath, and evaporating the liquid from said material, thereby leaving on its exterior and interstitial surfaces a dry adherent coating of graphite.

4. The process of making packing which includes immersing vegetable material in a liquid bath containing deflocculated graphite in suspension until the graphite particles have penetrated the tissues of said material, removing the material from the bath, and evaporating the liquid therefrom, thereby leaving in the tissues of the material and on the surfaces thereof a deposit of dry graphite.

5. The process of making packing which includes immersing porous material in a liquid bath containing deflocculated graphite in suspension, subjecting said bath with the porous material therein to the action of a vacuum to remove air from the pores of the said material, removing the porous material from the bath, and evaporating the liquid from the material, thereby leaving on its exterior and interstitial surfaces a dry adherent coating of graphite.

6. The process of making packing which includes immersing porous material in a liquid bath containing deflocculated graphite in suspension, subjecting said bath with the porous material therein to the action of a vacuum to remove air from the pores of the said material, subjecting the bath with the porous material therein to a pressure greater than atmospheric, removing the porous material from the bath, and evaporating the

liquid from the material, thereby leaving on its exterior and interstitial surfaces a dry adherent coating of graphite.

7. A packing consisting of a base material and a coating of graphite deposited from a liquid suspension of deflocculated graphite onto the base material and directly adherent thereto, the adhesion of the graphite being independent of the liquid suspending medium.

8. A packing consisting of a porous body and a coating of graphite deposited from a liquid suspension of deflocculated graphite onto the body and directly adherent to the surface of the body and to its interstitial surfaces, the adhesion of the graphite being independent of the liquid suspending medium.

9. A packing consisting of a body of fibrous material and coatings of graphite deposited from a liquid suspension of deflocculated graphite onto said body and di-

rectly adherent to the fiber of said material, the adhesion of the graphite being independent of the liquid suspending medium. 25

10. A packing consisting of a body of vegetable material and graphite deposited from a liquid suspension of deflocculated graphite onto said body and directly adherent to the exterior surfaces and to the tissues of said material, the adhesion of the graphite being independent of the liquid suspending medium. 30

11. A packing consisting of a body of fibrous vegetable material and graphite deposited from a liquid suspension of deflocculated graphite onto said body and directly adherent to the exterior surfaces and to the tissues of the fibers of said material, the adhesion of the graphite being independent 35 40 of the liquid suspending medium.

In testimony whereof, I hereunto affix my signature.

BURNIE L. BENBOW.
